CONTACT APPARATUS.

Application filed July 16, 1924. Serial No. 726,251.

Our invention relates to apparatus intended primarily for causing a gas or vapor to contact with a liquid and in particular to a form of apparatus which may be used in small columns or towers, such for example as the column which forms part of a rectifying still.

In the accompanying drawings, we show two sections of such a column, the upper part being illustrated in section and the lower part having a portion broken away. In this view the bell in the upper half is shown as assembled at right angles to the bell in the lower half.

Referring to the illustrative example shown, the numeral 2 is used to designate sections of pipe which are connected together by couplings 3 and thereby make up a substantially continuous tube. Between each section of pipe 2 is inserted a plate 4 which is held tightly in place when the couplings 3 are screwed up. Attached to the plate 4, as by welding, is a bubble bell 5 which has a series of small apertures 6 adjacent the plate 4 and has a downwardly extending tube 7 in the center, which tube is open both at the top and bottom. The plate 4 is provided with a large central opening which receives a tube 8 considerably larger in diameter than the tube 7 but slightly smaller than the interior diameter of the bell 5. The tube 8 is attached to the plate 4 in any desired manner.

Screwed into the bottom of the tube 8 is a plate 9 having on its bottom a drip ring or groove 10. The tube 8 is provided with two openings or windows 11, and the bottom part of this tube serves as a cup into which tube 7 extends.

It is to be noted that the parts are so proportioned that a space is left between the bottom of one plate 9 and the top of the next lower bell 5; and that the tube 8 goes above the plate 4 until it approaches relatively close to the top of bell 5.

As is usual with such apparatus, it is intended that the liquid shall pass downward, whereas the gas or vapor to be contacted with the liquid is to pass upward.

When liquid is introduced at the top of the apparatus, it will fall on a plate 4 and the level will rise until the apertures 6 are covered. If at the same time the gas or vapor is rising in the apparatus under even slight pressure, this vapor will prevent the

liquid from flowing through the apertures 6 and into the space between the upper part of tube 8 and the sides of bell 5. The liquid level will then continue to rise until it overflows the top of bell 5 and flows down through tube 7. The lower part of tube 8 will then fill up with liquid until the liquid reaches the bottom of windows 11, when it will flow out around the outside of tube 8 and strike plate 9 and fall against the outer portion of the next lower plate 4. The upwardly rising gas cannot pass up through tube 7 as a liquid seal is provided against this passage, but will enter windows 11 and pass over the top of tube 8, down under bell 5 and emerge through apertures 6 in the form of bubbles which will keep the liquid which surrounds bell 5 in a state of agitation so that close contact between the liquid and the vapor is obtained.

In an apparatus of this kind the effectiveness depends largely upon the area available for the openings 6 (in other words, upon the outside circumference of the bell 5), and by the arrangement here shown the bell 5 can be made of a diameter closely approximating the inside diameter of the pipe sections 2. For example, we have found that an apparatus can be made which will work with great success for laboratory purposes where the pipe sections 2 have an outside diameter of $2\frac{1}{4}$ inches and the bell 5 has an outside diameter of $1\frac{1}{2}$ inches, with the other parts arranged in the proportions shown in the drawings.

It is to be understood that the details and the manner of assembly of the device may be varied in many particulars without departing from the spirit of our invention and that the example shown in the drawings and which we have described in detail is intended by way of illustration only. In the annexed claims it is to be understood that the term "vapors" is intended to include both gases and vapors and that the word "central" as applied to the location of the passage for the downward flow of liquid is not intended to limit such location to one where such passage and the bell are necessarily concentric.

What we claim is:

1. In an apparatus of the character described the combination of a tube, plates in the tube and bubble bell assemblies attached to said plates, each such assembly

comprising a bubble bell having a series of openings around its periphery and a passage for the downward flow of liquid through its center, a cup into which such passage leads to provide a liquid seal and a passage for the upward flow of a vapor or the like between said liquid passage and the outer wall of the bubble bell.

2. In an apparatus of the character described, the combination of a tube, plates in the tube, holes in the plates, walls surrounding the peripheries of said holes, bells covering all of said walls on said plates, with openings between the tops of the walls and the underside of the bells, openings around the peripheries of the bells, pipes of an external diameter smaller than said holes leading through the center of the bells and opening through the tops thereof, and means for providing a liquid seal for the lower ends of said pipes whereby when a gas or vapor is forced under pressure in at the bottom of the tube and a liquid is allowed to flow in at the top, the liquid on each plate will be maintained at a uniform level substantially equal to the level of the top of a bell, and liquid in order to flow from one plate to a lower plate must pass through the ring of bubbles escaping from the periphery of a bell and thence over the top of a bell and down said central pipe, and gas or vapor must rise through liquid flowing towards such bell.

3. In an apparatus of the character described, a tube, a series of plates, an opening in one of said plates, a bell covering said

opening having apertures for the emission of vapor or gas around its periphery, a down pipe through said bell opening through the top of the bell and extending below said plate, means for forming a liquid seal for the bottom of said down-pipe and means for delivering liquid to said plate from a higher plate onto a zone not covered by such a bell, so that if a gas or vapor is forced into the bottom of said tube and liquid is allowed to flow in at the top, liquid which flows onto said plate can only reach said down-pipe by flowing through the ring defined by the bubbles of gas or vapor escaping from said bell.

4. In an apparatus of the character described, the combination of a tube, plates at various vertical points in the tube, holes in such plates, a bell covering each such hole in such plates, said bells having passages for the emission of gas or vapor about the peripheries thereof, down-pipes opening through the tops of such bells, and means for causing a liquid seal to form for such pipes and for directing liquid which flows down through any such pipe onto a lower plate at a zone not covered by a bell, whereby if a gas or vapor is forced in under pressure at the bottom of the tube and a liquid is allowed to flow in at the top, liquid in order to flow from one of such plates to a lower plate must pass through the ring defined by the bubbles escaping from the periphery of a bell on such plate.
